DESIGN FOR AN AIRPLANE

Wallace H. McLauchlan, Los Angeles, Calif.

Application August 17, 1945, Serial No. 121,479

Term of patent 14 years

(Cl. D71—1)

To all whom it may concern:

Be it known that I, Wallace H. McLauchlan, a citizen of the United States, residing at Los Angeles, in the county of Los Angeles and State of California, have invented a new, original, and ornamental Design for an Airplane, of which the following is a specification, reference being had to the accompanying drawings, forming part thereof.

In the drawings:

Fig. 1 is a top plan view of an airplane embodying my design.

Fig. 2 is a front elevational view of the airplane.

Fig. 3 is a side elevational view of the airplane. The opposite side of the airplane is substantially the same in appearance as the side illustrated in this figure.

Fig. 4 is a view in perspective of the airplane with landing gear in retracted position.

Fig. 5 is a sectional view taken on the line 5—5 of Fig. 3; and

Fig. 6 is a sectional view taken on the line 6—6 of Fig. 3.

I claim:

The ornamental design for an airplane, substantially as shown.

WALLACE H. McLAUCHLAN.
